WRENCH CONSTRUCTION

Leonard W. Johnson, deceased, late of Batavia,
Ill., by Helena E. Johnson, executrix, Batavia,
Ill., assignor to Helena E. Johnson

Application December 15, 1941, Serial No. 423,076

3 Claims. (Cl. 81—53)

This invention relates to tension wrenches, and has particular reference to a wrench of the slip joint variety having a circular work engaging boss with two oppositely disposed latch members on each side of the boss, and two handles, whereby a balanced thrust is maintained upon the work engaging boss and through the use of the two oppositely disposed handles a balanced torsional movement is imparted to the wrench, obviating the possibility of side strain or friction due to the canting of the parts in the wrench itself, whereby the wrench is rendered more accurate in service than wrenches of this type heretofore employed.

Another object of this invention is the provision of a torsion wrench having a pair of oppositely disposed handles to enable efficient operation of the wrench to be secured and likewise to render the wrench available for use with either hand in turning down nuts, so that during use of the wrench if the hand of the operator becomes tired he can change to the other hand, a desirable feature because of the speed with which these wrenches are used on assembly lines, reaching as high as twenty pulls per minute in some classes of work.

A further object of the invention is the provision of a wrench of the slip joint variety in which a pair of latch members in frictional engagement with a boss is used, the force of the boss which is exerted upon the workpiece being determined by the amount of friction between the latch members, and in which it is desirable to reduce to the lowest possible point the friction of other operating parts of the wrench or at least render the wrench uniform in its operation.

Another and further object of this invention is the provision of a torsion wrench having oppositely disposed balance thrust members so that the boss is held in balanced relation at all times, and to this extent is an improvement upon the wrench described and claimed in the copending application of Leonard W. Johnson, Serial No. 383,486, filed March 15, 1941.

A still further object of the invention is the provision of a torsion wrench of the slip joint variety in which the movement is limited, but which is provided with a stop operating after the joint of the wrench has slipped, so that nuts, such as castellated nuts, can be turned to secure registry of the slots in the nuts with holes through the bolts, for insertion of cotter pins. It further provides a wrench by which nuts can be backed off, if desired, or which when set can be backed up and re-set to secure accuracy. This is necessary at certain times due to the inaccuracy of the

fit between the threads on the nut and the bolt, which can be determined by the operator while the nuts are being turned down.

Another and further object of the invention is the provision of a tension wrench in which all sight indicating means are eliminated in the wrench, because it has been found that it is impossible for an operator to properly pull these tension wrenches and at the same time keep his attention fixed on sight indicating means.

These and other objects of the invention will be more fully and better understood by reference to the accompanying sheet of drawings, and in which—

15 Figure 1 is an elevational view of my improved wrench;

Figure 2 is a plan sectional view of the operating parts at one end of the wrench; and

Figure 3 is a vertical sectional view taken 20 through the center of Figure 2.

Referring now specifically to the drawing, and in which like reference characters refer to like parts throughout, a circular head 10 is provided having oppositely extending hollow arms 11 and 25 12 projecting therefrom, to which hollow extensions 13 and 14 are secured by means of rivets 15, 15 or any other appropriate fastening means. To the outer ends of the hollow extensions 13 and 14, respectively, are mounted hollow handles 16, 16, the extensions 13 and 14 extending into sockets formed in the handles 16, 16 respectively, and being secured in position by means of screws 16a, 16a.

Mounted within the circular head 10 is a boss 17 having trunnions 18 and 19 axially positioned 35 upon the boss 17 upon each side thereof, the trunnion 19 being extended to form a squared end 20 forming a work-engaging member and adapted to fit in the usual cap used for securing a wrench to nuts in the operation of wrenches of this type. The trunnion 18 is fitted into an opening formed in the head 10, while the opposite trunnion 19 is fitted into an opening formed in a cap 21 which is secured to the head 10 in

45 any approved manner and which serves to hold the boss 17 in operative position in the head 10. The boss 17 has recesses 22 and 23 formed therein, with walls 24 and 25 at one side of the recesses which are inclined slightly rearwardly from a radial line extending across the face of the boss 17 and from the center thereof, these recesses being positioned on opposite sides of the outer periphery of the boss 17. Another recess 26 is formed in the outer periphery of the boss 17, within 50 which a stop 27 is positioned, this stop having a

threaded end 28 which is in engagement with the threaded opening formed through the wall of the head 10. The stop 27 prevents the head 10 from rotating about the boss 17 except in a limited manner, and enables the wrench to be used for the tightening of nuts slightly beyond the tension for which the wrench is set, if desired, to secure proper registry of the channels in castellated nuts during the operation of the wrench.

A pair of latch members 28 and 29 is mounted in the arms 11 and 12, respectively, these latch members having angularly disposed faces which fit against the boss 17 at the bottom of the recesses 22 and 23, respectively, and have slightly rounded nose portions 30, 30 so that during continuous operation of the wrench they are not apt to crack the boss adjacent the walls 24 and 25 of the boss 17. Springs 31 and 32 are mounted in the extensions 13 and 14, respectively, with followers 33, 33 being provided which have indicators 34, 34 thereon. These indicators extend through slots 35 in the extensions 13 and 14, and are adapted to indicate pressures by graduations appearing upon plates 36, 36 secured to the extensions 13 and 14, respectively. Threaded members 37 are mounted in webs 38 forming part of the handle 16, and extend rearward with squared recesses 39 therein for the reception of a wrench or other appropriate tool by means of which the proper and desired compression may be placed upon the springs 31 and 32 to secure the desired friction between the latch members 28 and 29 and the boss 17. Rubber finger grips 40, 40 are provided on the handles 16, 16, respectively, to provide ease and sureness of grip for the operator in using the wrench. A grease nipple 41 is mounted in the wall of the head 10 so that lubricant can be forced through this member into the interior of the head 10 and around the boss 17 for properly and adequately lubricating the working parts of the wrench.

In operation of the wrench it will be understood that the threaded members 37 are set to the proper location to secure the desired compression on the springs 31 and 32, this compression being measured by the graduated markings appearing upon the plates 36, 36, which has been predetermined. If it is desired to turn a nut down to, say, 80 pounds tension, the figure now commonly accepted to be the proper one in most automobile motors, the members 37 can be turned until each one of them registers 40 pounds, one-half of the desired tension, and the wrench used to turn the nut down in the usual manner. When the desired resistance of the nut is reached, the latch members will slip in the recesses, not entirely out of them but enough so the operator can feel the slippage as he is pulling on the handles, allowing the head 10 to rotate a slight distance around the boss 17 or until it engages on stop 27. This will be sufficient to indicate to the workman that the desired tension has been reached and the wrench can be removed and applied to another nut. The stop performs the function also of preventing the wrench from spinning around on the boss, which might result in injury to a workman if, in pulling a nut up, his foot should slip on a greasy floor when the nut has been turned to the desired tension and the wrench released.

If, because of imperfections in the thread, the workman is not satisfied that the nut is fitted properly on the bolt at the tension desired, the force on the wrench is reversed by turning it in a counterclockwise direction, in which position

the latch members 28 and 29 engage against the surfaces 24 and 25 so that the nut can be backed up or loosened slightly or removed entirely if desired, and then pulled down to the set position again. Due to some irregularities in the threads, this may become necessary, and the workman can easily detect this irregularity by the action of the wrench as the nut is turned down, through the "feel" of the wrench in his hands.

10 In turning a nut down it is desirable that the operator grasp one of the handles in each hand and exert a movement on the wrench in a clockwise direction. Due to the fact that both the springs 31 and 32 are placed under the same compression, the boss is, in effect, placed in a floating position inside of the head 10 and there is not the tendency to cant, producing friction on one side of the trunnions 18 and 19, as would be the case if only one latch member were used or they were placed in any other than oppositely disposed positions to each other. Because of the fact that these latch members 28 and 29 are exerting a pressure upon the boss 17 in opposite directions, the full force of the rotative movement of the handles is applied directly to the boss 17 so that friction loss is overcome and the wrench is more accurate than if these opposed members were not used.

15 It has been found in practice that accuracy in turning down nuts, particularly upon heads of motors, is highly desirable because if they are not turned down uniformly the expansion and contraction of the metal making up the walls of the cylinder may distort the cylinder until it is out of round, causing loss of power, oil leakage and improper functioning of the motor. Therefore, through the use of the opposed latch members the accuracy of the wrench is materially increased, thereby adding materially to its effectiveness in applying nuts under the proper tension in a variety of operations, particularly with respect to internal combustion engines of all types used in automobiles, airplanes, trucks and the like.

20 45 While having described more or less precisely the details of construction, it is not wished to be understood as being limited thereto, as changes in form and the proportion of parts and the substitution of equivalents as circumstances may suggest or render expedient may be made without departing from the spirit or scope of the appended claims.

50 55 What is claimed is:

1. A tension wrench comprising in combination a head portion having oppositely extending hollow arms thereon, a work engaging boss mounted for rotative movement in said head having a pair of oppositely positioned latch receiving recesses in the outer periphery thereof in normal alignment with the said arms, latch members in said arms in frictional engagement with the said boss, hollow extensions secured to said arms, handles on the ends of the said extensions, springs in said extensions, followers in abutting engagement with the said springs, indicators on said followers, a threaded member in said handles whereby the compressive force on the said springs may be kept in balanced relation with each other, and cooperating means on said boss and said head whereby rotative movement of these two elements is limited to an extent which prevents disengagement of said latch members from said latch receiving recesses.

2. A tension wrench comprising in combination a head portion having oppositely extending hol-

low arms thereon, a work engaging boss mounted for rotative movement in said head having a pair of oppositely positioned latch receiving recesses in the outer periphery thereof in normal alignment with the said arms, latch members in said arms in frictional engagement with the said boss, means connected to said arms for adjusting in balanced relation the force of the frictional engagement of said latch members with said latch receiving recesses, said head also having a stop receiving recess in the outer periphery thereof between said first mentioned recesses, and a stop extending through the said head and into the stop receiving recess in the said boss, the stop receiving recess being wider than the stop to permit limited relative rotation between the head portion and the boss to an extent insufficient to allow a complete disengagement of said latch members from said latch receiving recesses.

3. A tension wrench comprising in combination 20 a head portion having oppositely extending hollow arms thereon, a work engaging boss mounted for rotative movement in said head having a

pair of oppositely positioned latch receiving recesses in the outer periphery thereof in normal alignment with the said arms, latch members in said arms in frictional engagement with the said boss, hollow extensions secured to said arms, handles on the ends of the said extensions, springs in said extensions, followers in abutting engagement with the said springs, a threaded member in said handles whereby the compressive force on the said springs may be kept in balanced relation with each other, a stop receiving recess in the outer periphery of said work engaging boss, and a stop extending through the said head and into the stop receiving recess in the said boss, the stop receiving recess being wider than the stop and sufficiently narrow to permit limited movement of the head with respect to the boss and to prevent the latch members from moving entirely out of the latch receiving recesses.
